CLAIM

(57) The ornamental design for a foot-actuated shopping cart brake as shown and described.

DESCRIPTION

FIG. 1 is a top view of a foot-actuated shopping cart brake, showing my new design.

FIG. 2 is a bottom view of the claimed design.

FIG. 3 is a left side view of the claimed design.

FIG. 4 is a right side view of the claimed design.

FIG. 5 is a rear view of the claimed design.

FIG. 6 is a front view of the claimed design.

FIG. 7 is a perspective view of the claimed design; and, FIG. 8 is another left side view of the claimed design showing environmental structure.

The dash-dot-dot-dash broken lines seen in FIG. 8 depict environmental structure and form no part of the claimed design.

1 Claim, 3 Drawing Sheets(56)
